UNITED STATES PATENT OFFICE.

FREDERIC E. WELLS, OF GREENFIELD, MASSACHUSETTS.

TAP-WRENCH.

1,099,681.

Specification of Letters Patent.

Patented June 9, 1914.

Application filed July 24, 1913. Serial No. 780,990.

To all whom it may concern:

Be it known that I, FREDERIC E. WELLS, a citizen of the United States of America, residing at Greenfield, in the county of Franklin and State of Massachusetts, have invented certain new and useful Improvements in Tap-Wrenches, of which the following is a specification.

This invention relates to a tap-wrench for the manipulation of taps or other similar devices, and it is designed particularly to be efficient, simple in operation, and cheap of construction.

Among its most important features, my invention comprises a tap-wrench involving a sleeve, two handles and two screws, all assembled in a strong, durable, and mechanically efficient manner.

In the drawings, Figure 1 represents a side elevation of my device; Fig. 2 is a cross-section of the same; and Fig. 3 is a bottom plan view thereof.

The tap-wrench comprises a sleeve *a* provided with a suitable aperture *b* through which the end of the tap may be passed. Suitably secured in the sleeve *a* is the handle *c* by means of the rivet *d*, or other equivalent device, and provided with, in this instance, the angle-face *e*. Slidably mounted in the other extremity of the sleeve *a* is another handle *f* provided with, in this instance, the double angle-face *g* and further with a recess *h* and with the cut-away por-

tion *i* forming the shoulder *j*. The sleeve *a* carries a screw *k* which, by engagement with the slot *l* hereinabove described, limits the play of the handle *f* (see Fig. 2). Mounted in an incline in the sleeve *a* is a set-screw *l* whose square forward end *m* abuts against the shoulder *j* upon member *f* hereinabove described. It is obvious that by manipulating the set-screw *l* the handle *f* may be adjusted with relation to the handle *c* to take any size tap or other similar instrument while the screw *k* and slot *l* prevent the device from falling apart unless purposely taken apart.

Having now described my invention, but recognizing that many changes and modifications may be made from the specific forms in which I have chosen here to illustrate it without departing from the scope of the invention, which is more truly bounded and defined by the claim hereto appended, I claim,—

A tap wrench, comprising, a stock, one of the handles slidable in said stock and formed at their ends to engage the tap, a shoulder on one of said handles, a screw threaded in said stock at an angle to said last named handle and adapted to bear on said shoulder.

FREDERIC E. WELLS.
